[57] ABSTRACT

A concrete form tie clamp for retaining a form wall or

9 Claims, 6 Drawing Figures

plurality of panels in a selected position during the pouring of the concrete within the structure and the form tie clamp is removably clamped on a rod or member of the structure and extending outwardly from a form wall and in a position having one end of a clamping or stop structure in engagement with said form wall. The clamping or stop structure includes first and second housing each of which have a respective cavity therein to receive and retain a respective one of first and second clamping members therein and each selectively movable into clamped engagement with a respective portion of the exterior surface of the rod or member in response to movement of a lever member pivotally mounted on one of the housings and having laterally spaced arms pivotally mounted on one end of the lever member and engageable with the other housing. A keeper member is pivotally mounted on the lever member and is selectively engageable with the rod for retaining the lever member and arms in position thereby holding the clamping members in frictional and clamped engagement with the rod and a plurality of latch members are mounted on one of the housings and engageable with the other housing for cooperating with the keeper member to hold the housings in position with the clamping members in clamped and frictional engagement with the rod.

CONCRETE FORM TIE CLAMP

The present invention relates to concrete form tie clamps and, more particularly, to a form tie clamp adapted to be clamped on a rod or member extending from a form wall and thereby hold the form wall in a selected position during depositing concrete thereagainst.

The principle objects of the present invention are: to provide a concrete form structure including a form tie clamp for retaining a form wall in a selected position during depositing concrete thereagainst; to provide such a form tie clamp for use in holding widely spaced form walls in selected positions during pouring of concrete within the form; to provide such a form tie clamp adapted to be clamped on a reinforcing bar, rod or like member extending from a form wall; to provide such a form tie clamp taking advantage of the high coefficient of friction of rubber, plastic or other resilient material to metal as compared to the coefficient of friction of metal to metal; to provide such a form tie clamp having positive means to hold the form tie clamp on the bar rod or like member extending from the respective form wall; and to provide such a form tie clamp which is easily installed and easily removed, economical to manufacture, durable in construction, positive in operation, and particularly well adapted for the proposed use.

Other objects and advantages of this invention will become apparent from the following description taken in connection with the accompanying drawings wherein are set forth, by way of illustration and example, certain embodiments of this invention.

The drawings constitute a part of the specification and include an exemplary embodiment of the present invention and illustrate various objects and features of the form tie clamp for retaining a form wall in a selected position during depositing concrete thereagainst.

FIG. 1 is a transverse sectional view through a concrete form with a side elevation of a form tie clamp embodying features of the present invention in an open position.

FIG. 2 is an enlarged side elevational view of the form tie clamp shown in a closed position to retain a form wall in position during placing concrete thereagainst.

FIG. 3 is an enlarged top plan view of the closed form tie clamp.

FIG. 4 is an enlarged end elevational view of the form tie clamp and shown in the closed position.

FIG. 5 is an enlarged transverse sectional view taken on line 5—5, FIG. 2.

FIG. 6 is a fragmentary enlarged transverse sectional view taken on line 6—6, FIG. 2 and showing one of a plurality of latch members.

Referring more in details to the drawings:

As required, detailed embodiments of the present invention are disclosed herein, however, it is to be understood that the disclosed embodiments are merely exemplary of the invention which may be embodied in various forms. Therefore, specific structural and functional details disclosed herein are not to be interpreted as limiting but merely as a basis for the claims and as a representative basis for teaching one skilled in the art to variously employ the present invention in virtually any appropriately detailed structure.

In the disclosed embodiment of the present invention, the reference numeral 1 generally designates a

form tie clamp for retaining a form wall 2 of a concrete form structure in a selected position and spacing from a facing form wall of the concrete form structure during depositing or pouring concrete thereagainst and into a space between facing form walls. The form tie clamp 1 is removably clamped on an elongated member, such as a rod or bar 3, extending outwardly from the form wall 2 and the form tie clamp 1 is in a position having an abutment at one end 4 of each of first and second housings 5 and 6 in engagement with an exterior surface of the form wall 2. The illustrated form tie clamp 1 includes clamping means illustrated as first and second housings 5 and 6 having cavities 7 and 8 respectively therein to receive and retain first and second clamping members 9 and 10 respectively each movable into clamped frictional engagement with a respective portion of the exterior surface of the elongated rod or bar 3 in response to movement of a lever member 11 pivotally mounted on one of the housings, for example the first housing 5, and having laterally spaced arms 12 and 13 pivotally mounted on one end 14 of the lever member 11 and engageable with the other or second housing 6. A keeper member 15 is pivotally mounted on the lever member 11 and is selectively engageable with the rod or bar 3 thereby retaining the lever member 11 and the arms 12 and 13 in position thereby holding the clamping members 9 and 10 in frictional and clamped engagement with the rod or bar 3 and latch means 16 are mounted on one of the housings, for example the second housing 6, and engageable with the other or first housing 5 for cooperating with the keeper member 15 to hold the first and second housings 5 and 6 in position with the clamping members 9 and 10 in clamped and frictional engagement with the rod or bar 3.

The first and second housings 5 and 6 of the clamping means are formed by respective walls arranged to define the cavities 7 and 8 respectively therein. The first housing 5 and the second housing 6 are positioned in facing relation. In the illustrated structure, side walls 17 and 18 define the first housing 5 and the second housing 6 respectively. Opposite ends 19 and 20 of the first housing 5 are closed by suitable end walls to define the cavity 7 in the first housing 5. Opposite ends 21 and 22 of the second housing 6 are closed by suitable end walls to define the cavity 8 therein the opposite end walls of the first and second housings 5 and 6 each have a respective passage or slot therein to permit the rod or bar 3 to extend therethrough.

The side walls 17 and 18 of the first and second housings 5 and 6 respectively may be any suitable shape to cooperate with the respective end walls to define the cavities 7 and 8 respectively therein. In the illustrated structure, the side walls 17 and 18 are semi-circular in cross-section and the side wall 17 has opposite side flanges 23 and 24 extending outwardly therefrom. The side wall 18 has opposite side flanges 25 and 26 extending outwardly therefrom. The side flanges 23 and 24 extending from the side wall 17 are positioned in facing relation with the respective adjacent side flanges 25 and 26 respectively extending from the side wall 18 when the first and second housings 5 and 6 are positioned in a closed position.

The first and second clamping members 9 and 10 of the clamping means are positioned in the cavities 7 and 8 of the first and second housings 5 and 6 respectively. The first and second clamping members 9 and 10 have

facing surfaces defining elongated recesses 27 and 28 respectively therein. The recessed defining surfaces are each frictionally engageable with a respective opposite portion of the exterior surface of the elongated rod or bar 3.

The first clamping member 9 has opposite ends 29 and 30 engageable with the end walls at the opposite ends 19 and 20 of the first housing 5. The second clamping member 9 has opposite ends 31 and 32 engageable with the end walls defining the opposite ends 21 and 22 respectively of the second housing 6 whereby the first clamping member 9 is retained within the first housing 5 and the second clamping member 10 is retained in the second housing 6 when in clamped frictional engagement with the elongated rod or bar 3.

The clamping members 9 and 10 may be formed of any suitable resilient material adapted to conform to the shape of the exterior surface of the elongated rod or bar 3 extending outwardly from the form wall 2. Hard rubber and various plastics have been found to provide the desired characteristics of sufficient deformation to conform to the exterior surface of the elongated rod 3 when same is a deformed reinforcing rod, such as used in concrete construction. Hard rubber and the plastics have a substantially higher coefficient of friction when in engagement with metal, such as the elongated reinforcing rod or bar 3, than the coefficient of friction of metal to metal engagement.

Means are mounted on one of the first and second housings 5 and 6 and in engagement with the other of the first and second housings 5 and 6 for selectively moving the housings one toward the other and thereby moving the first and second clamping members 9 and 10 into clamped engagement with the respective portion of the exterior surface of the elongated rod or bar 3 extending outwardly from the respective form wall 2.

In the illustrated structure, the means for moving the clamping members 9 and 10 into clamped and frictional engagement with the rod or bar 3 includes a standard extending outwardly from the side wall 17 of the first housing 5. The standard is positioned intermediate the opposite ends 19 and 20 of the side wall 17. The standard is illustrated as being formed of laterally spaced ears 33 and 34 extending substantially radially outwardly from the side wall 17 of the first housing 5 to receive the lever member 11 therebetween.

The lever member 11 is pivotally mounted on the standard and in the illustrated structure, is positioned between the ears 33 and 34 and the lever member 11 has the one end 14 and an other end 35 thereof each positioned on respective opposite sides of the standard. The lever member 11 is illustrated as an elongated planar member positioned between the spaced ears 33 and 34 and pivotally mounted thereon, as by a suitable shaft 36 mounted on and extending between the ears 34 and 33.

The lever member 11 has means pivotally mounted on the one end 14 thereof and engageable with the second housing 6 whereby movement of the other end 35 of the lever member 11 toward the first housing 5 moves the second housing 6 toward the first housing 5 to thereby move the clamping members 9 and 10 into clamped and frictional engagement with respective portions of the exterior surface of the rod or bar 3.

In the illustrated structure, the arms 12 and 13 have respective portions 37 and 38 thereof pivotally mounted on the one end 14 of the lever member 11.

The arm 12 has opposite end portions 39 and 40 extending from respective opposite ends of the intermediate portion 37. The opposite ends portions 39 and 40 of the arm 12 extend through the facing side flanges 23 and 25 of the first and second housings 5 and 6 respectively. The second arm 13 has opposite end portions 41 and 42 extending from respective opposite ends of the intermediate portion 38 thereof and extending through the facing side flanges 24 and 26 of the first and second housings 5 and 6 respectively. The opposite end portions 39 and 40 of the first arm 12 have enlarged portions 43 and 44 engageable with an outwardly facing surface of the side flange 25 of the second housing 6. The opposite end portions 41 and 42 of the second arm 13 have enlarged portions 45 and 46 thereon and engageable with the outwardly facing surface of the side flange 26 of the second housing 6 whereby the arms 12 and 13 move the side flanges 25 and 26 of the second housing 6 toward the side flanges 23 and 24 respectively of the first housing side in response to movement of the lever member 11. The enlarged portions are each illustrated as a suitable nut mounted on a threaded end of the respective end portion.

The form tie clamp 1 includes means associated with the first and second housings 5 and 6 respectively and with the means for moving the clamping members 9 and 10 into clamped frictional engagement with the rod 3 for retaining said clamped frictional engagement of the clamping members 9 and 10 with the exterior surface of the rod 3. In the illustrated structure, the keeper member 15 has one end 47 thereof pivotally mounted on the lever member 11 adjacent the other end 35 thereof. The other end 48 of the keeper member 15 has a return bend portion engageable with and surrounding at least a portion of the rod 3 and thereby maintaining the other end 35 of the lever member 11 in a selected spaced relation with the rod or bar 3.

The latch means 16 includes latch members 49 and 50 pivotally mounted on the side flange 25 of the second housing 6 and positioned adjacent the opposite end portions 39 and 40 respectively of the arm 12. Latch members 51 and 52 are also pivotally mounted on the side flange 26 of the second housing 6 and are positioned adjacent the end portions 41 and 42 respectively of the second arm 13. The latch members 49 and 50 are engageable with the side flange 23 of the first housing 5 and the latch members 51 and 52 are engageable with the side flange 24 of the first housing 5.

Each of the latch members has resilient means associated therewith and engageable with an outwardly facing surface of the respective side flange of the first housing 5 for urging the respective facing side flanges toward each other. In the illustrated structure, a washer 53 is sleeved on each of the latch members and is engaged by one end of a spring 54 having the other end thereof in engagement with an enlarged end portions 55. In the illustrated structure, the enlarged portion 55 is a nut mounted on a threaded end portion of the respective latch members.

In using a form tie clamp constructed as illustrated and described, the first and second housings 5 and 6 are positioned in surrounding relation with a reinforcing rod or bar 3 extending outwardly from the respective form wall 2. The one end 4 of the form tie clamp 1 is positioned in engagement with an exterior surface of the form wall 2 and the other end 35 of the lever member 11 is moved toward the reinforcing rod or bar 3.

The enlarged portions 43, 44, 45, and 46 thereby move the second housing 6 toward the first housing 5 and move the clamping members 9 and 10 into frictional and clamping engagement with respective portions of the exterior surface of the elongated rod or bar 3. The keeper member 15 is then moved to a position having the other end portion 48 thereof surrounding the rod 3. The latch members 49, 50, 51 and 52 are each moved to a position having the respective washer 53 thereon in engagement with the outwardly facing surface of the respective side flange of the first housing 5. The nuts defining the enlarged end portions 55 may be tightened as desired to compress the spring 54 and thereby hold the housings 5 and 6 in position with the clamping members 9 and 10 therein in clamped and frictional engagement with the rod or bar 3.

It is to be understood that while I have illustrated and described one form of my invention, it is not to be limited to the specific form or arrangement of parts herein described and shown.

What I claim and desire to secure by Letters Patent is:

1. A form tie clamp for retaining a form wall in a selected position during depositing concrete thereagainst, said form tie clamp comprising:

a. walls defining a first housing and a second housing each having a respective cavity therein, said first housing and said second housing being in facing relation, said first housing and said second housing each having a side wall and opposite end walls each having a passage therein to permit a rod extending outwardly from a respective form wall to extend therethrough, said first housing and said second housing each having opposite side flanges extending outwardly from said respective side wall thereof with the opposite side flanges of one of said housings being positioned in facing relation with said respective adjacent side flanges of the other of said housings;

b. a first clamping member and a second clamping member each positioned in the cavity in a respective one of said first housing and said second housing;

c. means mounted on the side wall of one of said first housing and said second housing and in engagement with the opposite side flanges of the other of said first housing and said second housing for selectively moving one of said first housing and said second housing toward the other housing and thereby moving said first clamping member and said second clamping member into clamped engagement with the rod extending outwardly from the respective form wall, said means for moving said clamping members into clamped engagement with the rod includes an elongated lever pivotally mounted on said side wall of said one housing and having the flange engaging means on one end thereof; and

d. means associated with said housings and said means for moving said clamping members into clamped engagement with the rod for retaining said clamped engagement of said clamping members with the rod, said means for retaining said clamped engagement of said clamping members with the rod includes means pivotally mounted on the other portion of said elongated lever.

2. A form tie clamp as set forth in claim 1 wherein said flange engaging means comprises:

a. first and second laterally spaced arms each having an intermediate portion thereof pivotally mounted on the one end of said lever member;

b. opposite end portions extending from each of said arms and extending through respective adjacent side flanges of said first and second housings; and

c. an enlarged portion on each of the end portions of each of said first and second arms and engageable with an outwardly facing surface of a respective side flange of the other of said first housing and said second housing to move same toward the facing side flange of the one housing in response to movement of said lever member.

3. A form tie clamp as set forth in claim 1 wherein said means for retaining said clamped engagement of said clamping members with the rod comprises:

a. a keeper member having one end thereof pivotally mounted on said lever member adjacent the other end thereof, the other end of said keeper member having a return bend engageable with and surrounding at least a portion of the rod to thereby maintain said lever member in a selected spaced relation with the rod;

b. first and second latch members pivotally mounted on each side flange of said other of said first housing and said second housing, said first and second latch members each being positioned adjacent a respective end of a respective side flange and engageable with the respective facing side flange of the one of said first housing and said second housing; and

c. resilient means associated with each of said first and second latch members on each side flange and engageable with the respective facing side flange for urging said respective facing side flanges toward each other.

4. A form tie clamp for retaining a form wall in a selected position during depositing concrete thereagainst, said form tie clamp comprising:

a. walls defining a first housing and a second housing each having a respective cavity therein, said first housing and said second housing being in facing relation, said first housing and said second housing each having a side wall and opposite end walls with said end walls each having a passage therein to permit a rod extending outwardly from a respective form wall to extend therethrough;

b. a first clamping member and a second clamping member each positioned in the cavity in a respective one of said first housing and said second housing;

c. means mounted on one of said first housing and said second housing and in engagement with the other of said first housing and said second housing for selectively moving one of said first housing and said second housing toward the other housing and thereby moving said first clamping member and said second clamping member into clamped engagement with the rod extending outwardly from the respective form wall, said means for moving said clamping members into clamped engagement with the rod includes means pivotally mounted on the other portion of said elongated lever.

1. a standard extending outwardly from said side wall of the one of said first housing and said second housing, said standard being positioned intermediate the ends of the one of said first housing and said second housing;

2. an elongated lever member pivotally mounted on said standard, said lever member having opposite ends positioned on respective opposite sides of said standard; and
3. means pivotally mounted on one of the opposite ends of said lever member and engageable with the other of said first housing and said second housing whereby movement of the other end of said lever member toward the one of said first housing and said second housing moves said other of said first and second housings toward said one of said first and second housings; and
- d. means associated with said housings and said means for moving said clamping members into clamped engagement with the rod for retaining said clamped engagement of said clamping members with the rod, said means for retaining said clamped engagement of said clamping members with the rod includes means pivotally mounted on the other end 20 of said elongated lever member.

5. A form tie clamp for use in a concrete form structure having spaced walls defining a space therebetween to receive concrete and a plurality of elongated members secured relative to one of said walls and extending 25 through the other wall and generally perpendicular thereto, said form tie clamp comprising:

- a. first and second abutment members each adapted to engage one of spaced walls of a concrete form structure and on a side thereof opposed to the side 30 facing a concrete receiving space therebetween, the one form wall having an elongated member extending therethrough and normal thereto, said first and second abutment members each having a passage therethrough to permit the elongated member 35 to extend through said first and second abutment members;

- b. first and second clamping members each connected to a respective one of said first and second abutment members, said clamping members each 40 comprising:

1. a housing having a side wall and opposite end walls positioned to define a cavity therein, said housing end walls each having a passage therein to permit the elongated member to extend there- 45 through; and

2. a resilient member within the cavity in said housing and having a surface defining an elongated recess therein, said surface being frictionally engageable with an exterior surface of the respective elongated member, said resilient member having opposite ends thereof engageable with said end walls of said housing whereby said resilient member is retained in said housing when in frictional engagement with the respective elongated member;

- c. means actuating said first and second clamping members to clampingly engage a respective elongated member extending through the one wall of the concrete form structure engaged by said first and second abutment members to thereby retain the one form wall in a selected spacing from the other form wall, said means actuating said first and second clamping members to clampingly engage 65 the respective elongated member comprising:

1. a standard extending outwardly from said side wall of said housing of one of said first and sec-

- ond clamping members and positioned intermediate the ends of said side wall;
  2. an elongated lever member pivotally mounted on said standard, said lever member having opposite ends positioned on respective opposite sides of said standard; and
  3. means pivotally mounted on one of the opposite ends of said lever member and engageable with said housing of the other of said first and second clamping members whereby movement of the other end of said lever member toward the one of said first and second clamping member moves said other of said first and second clamping members toward said one of said first and second clamping members and into engagement with the elongated member therebetween; and
  - d. means associated with said housings and said means actuating said first and second clamping members to retain the one form wall in a selected spacing from the other form wall for retaining said clamped engagement of said clamping members with the elongated member, said means for retaining said clamped engagement of said clamping members with the elongated member includes means pivotally mounted on the other of the opposite ends of said elongated lever member.
6. A form tie clamp as set forth in claim 5 wherein:
- a. said housing of each of said first and second clamping members has opposite side flanges extending outwardly from said respective side wall thereof and each positioned in facing relation the respective side flange of the other of said housings; and
  - b. said means pivotally mounted on one of the opposite ends of said lever member for moving said other of said first and second clamping members toward said one of said first and second clamping members and into engagement with said elongated member therebetween comprises:
1. first and second laterally spaced arms each having an intermediate portion thereof pivotally mounted on the one end of said lever member;
  2. opposite end portions extending from each of said arms and extending through respective adjacent side flanges of said housings of said first and second clamping members; and
  3. an enlarged portion on each of the end portions of each of said first and second arms and engageable with an outwardly facing surface of a respective side flange of said housing of said other of said first and second clamping members to move same toward the facing side flange of said housing of said one of said first and second clamping members in response to movement of said lever member.
7. A form tie clamp for retaining a form wall in a selected position during depositing concrete thereagainst, said form tie clamp comprising:
- a. walls defining a first housing and a second housing each having a respective cavity therein, said first housing and said second housing being in facing relation, said first housing and said second housing each having a side wall and opposite end walls with at least one of said end walls of each of said housings having a passage therein to permit a rod extending outwardly from a respective form wall to extend therethrough, said first housing and said second housing each have opposite side flanges ex-

- tending outwardly from said respective side wall thereof with the opposite side flanges of one of said housings being positioned in facing relation with said respective opposite side flanges of the other of said housings;
- b. a first clamping member and a second clamping member each positioned in the cavity in a respective one of said first housing and said second housing;
- c. means mounted on one of said first housing and 10 said second housing and in engagement with the other of said first housing and said second housing for selectively moving one of said first housing and said second housing toward the other housing and thereby moving said first clamping member and 15 said second clamping member into clamped engagement with the rod comprising:
1. a standard extending outwardly from said side wall of the one of said first housing and said second housing, said standard being positioned intermediate the ends of the one of said first housing and said second housing;
2. an elongated lever member pivotally mounted 20 on said standard, said lever member having opposite ends positioned on respective opposite sides of said standard; and
3. means pivotally mounted on one of the opposite 25 ends of said lever member and engageable with the other of said first housing and said second housing moves said other of said first and second housings toward said one of said first and second housings, said means pivotally mounted on one 30 of the opposite ends of said lever member for moving said other of said first and second housings toward said one of said first and second housings comprising:
- a. first and second laterally spaced arms each 40 having an intermediate portion thereof pivotally mounted on the one end of said lever member;
- b. opposite end portions extending from each of 45 said arms and extending through respective adjacent side flanges of said first and second housings; and
- c. an enlarged portion on each of the end portions of each of said first and second arms and 50 engageable with an outwardly facing surface of a respective side flange of the other of said first housing and said second housing to move same toward the facing side flange of the one housing in response to movement of said lever member; and
- d. means associated with said housings and 55 said means for moving said clamping members into clamped engagement with the rod for retaining said clamped engagement of said clamping members with the rod, said means for retaining said clamped engagement of said clamping members with the rod comprising:
1. a keeper member having one end thereof pivotally mounted on said lever member adjacent the other end thereof, the other end of said keeper member having a return bend engageable with 60 and surrounding at least a portion of the rod to

- thereby maintain said lever member in a selected spaced relation with the rod;
2. first and second latch members pivotally mounted on each side flange of said other of said first housing and said second housing, said first and second latch members each being positioned adjacent a respective end of a respective side flange and engageable with the respective facing side flange of the one of said first housing and said second housing; and
3. resilient means associated with each of said first and second latch members on each side flange and engageable with the respective facing side flange for urging said respective facing side flanges toward each other.
8. A form tie as set forth in claim 7 wherein:
- a. said first clamping member and said second clamping member each have a surface defining an elongated recess therein, said surfaces each being frictionally engageable with an exterior surface of the rod; and
- b. said first clamping member and said second clamping member each have opposite ends engageable with said end walls of said respective first housing and said second housing whereby said first clamping member is retained in said first housing and said second clamping member is retained in said second housing when in clamped frictional engagement with the rod.
9. A form tie clamp for use in a concrete form structure having spaced walls defining a space therebetween to receive concrete and a plurality of elongated members secured relative to one of said walls and extending through the other wall and generally perpendicular thereto, said form tie clamp comprising:
- a. first and second abutment members each adapted to engage one of spaced walls of a concrete form structure and on a side thereof opposed to the side facing a concrete receiving space therebetween, the one form wall having an elongated member extending therethrough and normal thereto;
- b. first and second clamping members each connected to a respective one of said first and second abutment members, said clamping members each comprising:
1. a housing having a side wall and opposite end walls positioned to define a cavity therein, said housing end walls each having a passage therein to permit the elongated member to extend therethrough, said housing of each of said first and second clamping members having opposite side flanges extending outwardly from said respective side wall thereof and each positioned in facing relation the respective side flange of the other of said housings; and
2. a resilient member within the cavity in said housing and having a surface defining an elongated recess therein, said surface being frictionally engageable with an exterior surface of the respective elongated member, said resilient member having opposite ends thereof engageable with said end walls of said housing whereby said resilient member is retained in said housing when in frictional engagement with the respective elongated member; and
- c. means actuating said first and second clamping members to clampingly engage a respective elongated member.

gated member extending through the one wall of the concrete form structure engaged by said first and second abutment members to thereby retain the one form wall in a selected spacing from the other form wall, said means actuating said first and second clamping members to clampingly engage the respective elongated member comprising:

1. a standard extending outwardly from said side wall of said housing of one of said first and second clamping members and positioned intermediate the ends of said side wall;
  2. an elongated lever member pivotally mounted on said standard, said lever member having opposite ends positioned on respective opposite sides of said standard; and
  3. means pivotally mounted on one of the opposite ends of said lever member and engageable with said housing of the other of said first and second clamping members whereby movement of the other end of said lever member toward the one of said first and second clamping member moves said other of said first and second clamping members toward said one of said first and second clamping members and into engagement with the elongated member therebetween, said means pivotally mounted on one of the opposite ends of said lever member for moving said other of said first and second clamping members toward said one of said first and second clamping members and into engagement with said elongated member therebetween comprising:
- a. first and second laterally spaced arms each having an intermediate portion thereof pivotally mounted on the one end of said lever member;
  - b. opposite end portions extending from each of said

5

35

arms and extending through respective adjacent side flanges of said housings of said first and second clamping members; and

- c. an enlarged portion on each of the end portions of each of said first and second arms and engageable with an outwardly facing surface of a respective side flange of said housing of said one of said first and second clamping members in response to movement of said lever member, said means actuating said first and second clamping members to retain said second side in a selected spacing from said first side including:
1. a keeper member having one end thereof pivotally mounted on said lever member adjacent the other end thereof, the other end of said keeper member having a return bend engageable with and surrounding at least a portion of the respective elongated member and thereby maintain said lever member in a selected spaced relation with said elongated member;
  2. first and second latch members pivotally mounted on each side flange of said housing of said other of said first and second clamping members, said first and second latch members each being positioned adjacent a respective end of a respective side flange and engageable with the respective facing side flange of said housing of the one of said first and second clamping members; and
  3. resilient means associated with each of said first and second latch members on each side flange and engageable with the respective facing side flange for urging said respective facing side flanges toward each other.
